Primary Examiner—Wallace R. Burke*Assistant Examiner*—J. Sincavage*Attorney, Agent, or Firm*—Terry M. Gernstein**[57] CLAIM**

The ornamental design for a combined electrical box and mounting block therefor, as shown and described.

DESCRIPTION

FIG. 1 is a perspective view of the combined electrical box and mounting block therefor embodying the design of the present invention;

FIG. 2 is a front elevational view thereof, the rear being a mirror image of the front shown in FIG. 2;

FIG. 3 is a left side elevational view thereof;

FIG. 4 is a right side elevational view thereof;

FIG. 5 is a top plan view thereof, the bottom view being a mirror image of the top view shown in FIG. 5; and,

FIG. 6 is a rear and lower left perspective view thereof.

FIG.1

FIG. 2

FIG. 3

FIG. 4
